The ornamental design for a toothbrush, as shown and described.

DESCRIPTION

FIG. 1 is a right front perspective view of a toothbrush according to the new design;

FIG. 2 is a left front perspective view thereof;

FIG. 3 is a right rear perspective view thereof;

FIG. 4 is a left rear perspective view thereof;

FIG. 5 is a front view thereof;

FIG. 6 is a rear view thereof;

FIG. 7 is a left side view thereof;

FIG. 8 is a right side view thereof;

FIG. 9 is a top view thereof; and,

FIG. 10 is a bottom view thereof.

The claim is limited to the neck portion of the handle and the slightly raised features on the rear midsection of the handle. The broken lines that are immediately adjacent the surface shading represent the bounds of the claim and form no part thereof. The broken lines showing the head and the remainder of the handle illustrate portions of the toothbrush that form no part of the claimed design.
